SOFA BED

Domenic Catalini, Fitchburg, Mass., assignor to
 Charlton Company, Inc., Fitchburg, Mass., a
 corporation of Massachusetts

Application March 7, 1947, Serial No. 732,957

2 Claims. (Cl. 155—184)

1

This invention relates to improvements in sofa beds of the type which are convertible from a position wherein the sofa bed assumes the function of and appears to be a conventional sofa to a position wherein the same is extended so that it may be used as a bed, taking advantage of the back rest as a part of the sleeping surface.

The principal object of the invention is to provide a sofa bed which has all the appearances of a conventional sofa; and the provision of a sofa bed which completely avoids the appearance of conventional sofa beds and assumes the appearance of a sofa of the non-convertible type, the invention residing in the provision of means whereby the front edge of the seating member is provided with a forwardly extending roll edge in the manner of a sofa, but particularly and peculiarly distinct from sofa beds of the prior art which have always been almost exactly vertical at the front edge thereof from the very bottom of the lower frame to the top edge at the front of the seating element, the present construction and invention resulting in a more comfortable and easier seating sofa as well as in giving the sofa bed the full and complete appearance of a sofa of the non-convertible type.

Further objects of the invention reside in the provision of a spring frame for the seat element of a sofa bed, said spring frame comprising a rectangular frame upon which is mounted a series of coil springs, there being a row of coil springs at the front edge of the frame, said coil springs extending considerably beyond the edge of the frame and overhanging the same at said edge thereof in combination with padding which is rolled over the outwardly extending edge of the springs above recited and brought down along the springs so as to form a rolled, outwardly extending edge which normally supports the under sides of the legs of the person sitting on the sofa, there being upholstery material covering the padding and extending down and under the frame, being secured thereto principally by means of a strip extending the length of the frame and having a height sufficient to form the rolled edge and maintain it in position, said strip being covered by similar upholstery material.

Other objects and advantages of the invention will appear hereinafter.

Reference is to be had to the accompanying drawings in which

Fig. 1 is a view in front elevation of the new sofa bed;

Fig. 2 is a section on line 2—2 of Fig. 1; and

Fig. 3 is a top plan view of the seat frame of 55

the sofa bed, parts being broken away and for clarity of illustration.

In the past it is always been considered necessary that a convertible sofa bed should have a straight seat front edge, and this straight edge has always immediately identified a sofa bed for what it is, as distinct from an ordinary sofa which is not convertible. This invention provides a construction obviating this deficiency in convertible beds and, at the same time, provides for added comfort to the occupant.

In Fig. 1 there is shown a lower frame 10 having side arm frames 12 which are more or less conventional in the art. There is also provided a seating element generally indicated at 14 having hinged thereto a back rest element 16 in the conventional manner so that the parts 14 and 16 may be positioned as shown in Fig. 1 or may be extended in parallelism as indicated in Fig. 2 to form a bed. The hinges are not shown as they are old and well known in the art.

The present invention concerns in particular the seat frame 14 and this is shown in detail in Figs. 2 and 3 wherein there is provided a rectangular flat frame 18 which forms a support for a series of coil springs 20, 22 and 24. Springs 20 will be located inwardly from the edges of the frame 18 in the conventional manner, the springs 22 are located along the rear edge of the frame and in general the springs 22 have a run as at 26 more or less on a vertical line with the rear edge of the frame 18.

The front row of springs 24, however, are arranged so that the outwardmost extent of said springs as shown at 28 lie outwardly beyond the extreme front edge of frame 18 so as to overlap the same as is clearly shown in Figs. 2 and 3. The upper runs of the spring may be secured together by a wire frame 30 and the individual springs may be clamped together by any desired means such as elements 32.

In the usual circumstances a cloth or burlap cover 34 is stretched over the top of the springs and over the burlap there is provided a layer of padding 36 which in the present instance is brought forwardly and down around the overlapping edge 28 of the coil springs 24 as indicated at 38. The upholstery material 40 is then applied to cover the padding and this upholstery is also brought down around the overhanging edges of springs 24 providing a rolled edge 42. The upholstery material 40 is then secured in any desired manner to the frame 18.

Strip 44 is then applied to the front of the spring frame 18 and this strip has a vertical

height sufficient to force the upholstery and padding inwardly as clearly shown in Fig. 2 to form and maintain the roll edge 42 in the position shown. A strip of upholstery material 46 is secured to the strip 44 by being brought around down under the same and then secured to the bottom of the spring frame at 48. In Fig. 2 the construction is shown as not quite yet completed for the purpose of illustrating the invention in a clearer manner. The reference numeral 44 is applied to Fig. 1 to indicate the position of the strip which forms and holds the rolled edge and it will be seen that this strip extends for the full length of the seat element 14.

Strips 50 are applied to the finished sofa bed and extend down to points 52 and further strips 54 are applied to the lower frame 10 to carry out the illusion of continuous strips forming individual cushions 56.

It will be seen that this invention provides for the first time in the art a sofa bed having the exact appearance of a conventional sofa and which, at the same time, provides for additional comfort to the occupants thereof particularly when seated on the device when it is in the sofa position of Fig. 1.

Having thus described my invention and the advantages thereof, I do not wish to be limited to the details herein disclosed otherwise than as set forth in the claims, but what I claim is:

1. A convertible sofa bed comprising a base, a seat, and a back, said seat comprising a rectangular frame, a series of springs thereon, certain of said springs projecting beyond a side edge of the frame at the front edge of the seat, padding rolled over the springs and projecting beyond the frame and said base, covering over the padding, and a

finish strip securing the covering to the frame and forming and maintaining the padding and covering in a forwardly projecting roll edge, said finish strip lying under the rolled padding and projecting springs and inwardly thereof as respects the said base.

2. In a convertible sofa bed having a base, a movable back and a seat, said seat comprising a frame, a series of conical coil springs small ends down on the frame, certain of said springs having portions of their larger turns overhanging a side edge of the frame, at the front edge of the seat, padding rolled over the springs at the overhanging portions of the said certain springs, covering over the padding, a strip the length of the sofa bed securing the covering to the frame vertically beneath the rolled over padding and overhanging spring portions and forcing the padding in toward the certain coil springs to form a projecting roll edge, and covering over the strip.

DOMENIC CATALINI.
